George W. Brooks, Inventor

C. Snow & Co.

UNITED STATES PATENT OFFICE.

GEORGE WASHINGTON BROOKS, OF COLUMBUS, TEXAS.

TRACE-CARRIER.

SPECIFICATION forming part of Letters Patent No. 429,224, dated June 3, 1890.

Application filed February 11, 1890. Serial No. 340,017. (No model.)

To all whom it may concern:

Be it known that I, GEORGE WASHINGTON BROOKS, a citizen of the United States, residing at Columbus, in the county of Colorado 5 and State of Texas, have invented a new and useful Trace-Carrier, of which the following is a specification.

This invention relates to harness, and is more particularly a trace-carrier connected to 10 the back-band thereof at its point of connection with the traces; and the same consists of a buckle composed of two parts having laterally-extending arms hinged together at their outer ends, whereby an open eye or loop is 15 produced for receiving the trace.

The invention also consists in certain details of construction, all as hereinafter described, and illustrated in the accompanying drawings, in which—

20 Figure 1 is a perspective view of my improved back-band buckle in position. Fig. 2 is a central transverse section. Fig. 3 is a perspective view of the buckle in its open position with the trace and back-band removed.

25 The letter B designates the back-band, the letter G the girth, and the letter T one of the traces, it being understood that the latter, although usually of leather, may sometimes be of metal—as a chain, for instance. The rela-

30 tive location and positions of these parts need not be further dwelt upon, as they are well known to every person skilled in this art.

My improved trace-carrier is composed of two members. The lower member L has a 35 large rectangular eye I in its body and is provided with an arm l. The upper member U has a large rectangular eye i in its body, which is of the same length but of less width than that in the lower member, and the outer bar 40 of this upper member is provided with teeth t, which take into the back-band B, as will be clearly understood. The upper member is also provided with an arm u, standing over the arm l, and these two arms are provided

45 at their outer ends with eyes, through which passes a pin P, thereby forming a hinge. Upon the ends of this pin is secured a loop-bar O, whereby a loop is formed, into which the strap g of the girth G is engaged. The upper arm 50 u is bent upwardly somewhat, whereby a space is formed between it and the lower arm

l, and through this space passes the trace T. In the upper arm is formed a longitudinal slot s, which loosely engages the head of a stud S, whose point projects across the space 55 between the two arms, as clearly shown in the drawings.

When my improved trace-carrier is to be put in place, the strap g of the girth G is secured in the loop O, after which the buckle is 60 opened to the position shown in Fig. 3 and adjusted longitudinally upon the trace T to the desired point. The back-band B is then passed outwardly through the eye I, over the teeth t, and inwardly through the aligned eyes 65 i and I, as shown in Fig. 1. The back-band being tightened to the desired tension, the upper member U is drawn down upon the lower member L, whereby the back-band is buckled within the device and the stud S is 70 caused to enter a hole in the trace T or one of the links of a chain-trace T, and is thereby also simultaneously buckled thereon. The device thereby serves the triple function of a buckle for the back-band, a buckle for the 75 trace, and a support for the girth, and both of these buckles are engaged simultaneously, as is highly desirable in devices of this character.

What I claim is—

1. In a trace-carrier, the lower member L, having an arm l, and the upper member U, having an arm u, said members being provided with registering eyes in their bodies, and said arms being hinged together at their outer 85 ends, substantially as described.

2. In a trace-carrier, the lower member L, provided with an enlarged eye I and having an arm l, and the upper member U, provided with an eye i, of the same length as but of 90 less width than the eye in the lower member, having teeth t on its outer edge, and having an arm u and a hinge at the outer ends of said arms, substantially as described.

3. In a trace-carrier, the lower member L, 95 having the arm l, and the upper member U, having the upwardly-bent arm u, provided with the slot s, said arms being hinged together, in combination with the stud S, having a head loosely engaging said slot, as and for 100 the purpose set forth.

4. In a trace-carrier, the combination, with

the lower member L, having an arm *l*, with eyes at its outer end, and the upper member U, having an arm *u*, with eyes at its outer end, of the pin P, passing through said eyes, 5 and the loop-bar O, engaging the ends of the pins and forming a loop, the whole constructed as and for the purpose set forth.

5. In a trace-carrier, the combination of the following instrumentalities, to wit: a lower 10 member L, provided with an eye I, an upper member U, provided with an eye *i*, of less width than the eye I, teeth *t* on the outer edge of said upper member, an arm *l*, projecting from the lower member and provided with 15 eyes in its outer end, an upwardly-bent arm

u, projecting from the upper member, having a slot *s* in its body and provided with eyes in its outer end, a stud S, whose head engages said slot, a pin P, passing through the eyes in the outer ends of said arms, and a looped bar 20 O, connected to the ends of said pin, the whole arranged and combined substantially as and for the purposes set forth.

In testimony that I claim the foregoing as my own I have hereto affixed my signature 25 in presence of two witnesses.

GEORGE WASHINGTON BROOKS.
